US0D1085128S

(12) **United States Design Patent** (10) **Patent No.:** **US D1,085,128 S**
(45) **Date of Patent:** **** Jul. 22, 2025**

(54) **DISPLAY PANEL OR PORTION THEREOF WITH A GRAPHICAL USER INTERFACE**

(71) Applicants: **CNH Industrial America LLC**, New Holland, PA (US); **CNH Industrial Italia S.p.A.**, Turin (IT)

(72) Inventors: **Andrea Maria Cardona Alfaro**, Skokie, IL (US); **Jared A. Heckart**, Danville, IA (US); **Courtney Achen, Jr.**, Mt Pleasant, IA (US); **George Wallace MacIntyre, Jr.**, Trevor, WI (US); **Marta Zippo**, Modena (IT); **Irene Cassini**, Turin (IT); **Simone Malvezzi**, Turin (IT); **Valerio Marcello Lorizzo**, Carpi (IT)

(73) Assignees: **CNH Industrial America LLC**, New Holland, PA (US); **CNH Industrial Italia S.p.A.**, Turin (IT)

(**) Term: **15 Years**

(21) Appl. No.: **29/914,573**

(22) Filed: **Oct. 19, 2023**

(51) LOC (15) Cl. **14-04**

CLAIM

The ornamental design for a display panel or a portion thereof with a graphical user interface, as shown and described.

DESCRIPTION

The FIGURE is a front view of a display panel or portion thereof with a graphical user interface, showing our new design.

The outermost broken lines illustrate a display panel, which is the environment of the design, and which forms no part of the claimed design. The remaining broken lines illustrate portions of the display panel, and portions of the graphical user interface, and form no part of the claimed design.
